UNITED STATES PATENT OFFICE.

HENRY O. ROBINSON, OF BROOKLINE, MASSACHUSETTS, AND CHRISTOPHER STEADMAN,
OF HUGUENOT PARK, NEW YORK.

BRICK-KILN.

1,168,556.

Specification of Letters Patent. Patented Jan. 18, 1916.

Application filed April 17, 1911. Serial No. 621,672.

To all whom it may concern:

Be it known that we, HENRY O. ROBINSON, a citizen of the United States, and a resident of Brookline, in the county of Norfolk and State of Massachusetts, and CHRISTOPHER STEADMAN, a subject of the King of Great Britain, residing at Huguenot Park, in the county of Richmond and State of New York, have invented an Improvement in 5
10 Brick-Kilns, of which the following is a specification, reference being had to the accompanying drawings, forming a part hereof.

The general object of the invention is to 15 provide a brick-kiln structure in which the burning of bricks may be carried on to considerable practical advantage with a forced-draft fire. The use of a forced-draft in brick-kilns enables cheaper grades of fuel to 20 be employed and reduces the time required for a burning; but, heretofore, attempts to use forced-draft furnaces in brick-kilns have generally failed because it was impossible to produce a uniform burning throughout 25 the kilns, whereby a considerable loss would result from overburning or underburning or both. We have discovered that by constructing the kiln and supplying the draft thereto in such a way that the fires 30 are always under complete control, we are able to secure a uniform burning throughout the kiln and to effect the burning with greater economy of fuel, time and percentum of perfectly burned brick than has 35 been possible heretofore under any method or practice with which we are familiar.

An important element in controlling the fires of forced-draft brick-kilns we have found to reside in their freedom from what 40 we may call draft-leakage. Where, for instance, the draft can work its way through the sides or bottom of the fire-box, an indeterminate and varying amount will find its way through the fuel-bed with the result 45 that anything like an accurate control is out of the question. Moreover, when a leak commences, it usually increases owing to the penetrating nature of the mixture of air and steam which is usually employed to produce 50 the draft. For this reason the bottom and sides of the fire-box, in order to secure the best results, must be impervious. We have already pointed this out in our Letters Patent No. 971,642 of October 4, 1910, where 55 we called attention to the importance of

making the ashpit tight. In the present case, we have the same ends in view, but have simplified the structure considerably, doing away, for instance, with the grate and distributing the draft by means of a relatively 60 long perforated conduit, preferably removable and portable, over and upon which the fuel is piled; and have otherwise improved said structure as will hereinafter appear.

In the accompanying drawings, to which 65 we may now refer for an understanding of the invention in detail, Figure 1 is a plan view of the floor of a portion of a kiln embodying the invention. Fig. 2 is a sectional view upon a larger scale, the plane of section being indicated by the line 2-2 in Fig. 1. Fig. 3 is a similar view, the plane of section being indicated by the line 3-3 in Fig. 1. Fig. 4 is a plan view of the draft supply pipe, and, Fig. 5 is a sectional view taken 70 through the perforated portion of said pipe, on a plane indicated by the line 5-5 in Fig. 3.

The bed of the improved kiln, that is the part which may or may not be composed of 80 the green brick being burned but which will generally be a permanent structure, comprises as shown, a floor *a* which presents a plurality of rows of chambers or depressions *b* constituting the fire-boxes, with 85 front and back walls *c* at the outer ends of the fire-boxes; and with which are employed means or mechanism for supplying and distributing the forced-draft to the fuel bed. The floor *a* is preferably constructed from 90 burnt bricks laid in cement mortar which provides a practicable air and water-tight structure. The latter may be about 18 inches deep and 14 inches wide, dimensions 95 which have been found to work well in practice, although, of course, those proportions may be varied; and they may extend completely across the kiln, or only part way as shown in the drawing. In the present case, the inner ends of these fire-boxes taper off or are stepped about one-third way in of the kiln from either side, their bottoms thus gradually rising to the level of the kiln floor. As many fire-boxes may be used as are required to effect the burning. It has 100 been found in practice that with the average clays, it is sufficient to arrange the fire-boxes of the above-named dimensions about 34 inches apart, whereby a wall of green brick, of about four 8-inch bricks in thickness ar. 110

ranged lengthwise, may be placed between adjacent fire-boxes. And in laying the green brick about the fire-boxes to form the arches above the fire-boxes, the green brick are preferably set back an inch or so from the edges of the fire-boxes in order to give them a firm rest upon the kiln floor. After the arches are formed the rest of the green brick is piled in the ordinary manner.

- 10 Extending along the center of the bottom of each depression or fire-box *b* for nearly its entire length is a perforated conduit or pipe *d*, preferably removable and portable, the perforated portion of which may rest 15 upon the bottom of the fire-box and the closed portion of which projects from the fire-box and is preferably upturned with its free open end *e* removed from the fire-box door *f*. Into this open end of the pipe *d* an 20 injector *g* is arranged to deliver steam in order to entrain air and produce a forced-draft, and the steam may be supplied from a suitable source through a pipe *h* to the several injectors *g*. The upwardly projecting 25 end of the pipe *d* is preferably offset so as not to come directly in front of the fire-box door, and the space between said pipe, where it projects from the fire-box, and the fire-box door is preferably filled with brick 30 and clay to form a tight closure.

While the conduit *d* may be constructed in various ways it is preferably embodied in a pipe having a perforated portion *d*¹ which is arranged along the bottom of the fire-box, 35 and an angular portion *d*² which is exterior to the fire-box. This angular portion consists of a section which is bent in a horizontal plane at substantially right-angles to the perforated portion and then bent again in 40 a vertical plane at substantially right-angles to itself. In this way, the pipe is provided with an upwardly extending portion having a free open end *e* into which steam may be delivered to entrain air and create a forced 45 draft, and with a means of maintaining the pipe in its proper position as it rests down upon the bottom of the fire-box. The latter means are obviously provided through the angularity of the exterior or closed portion 50 of the pipe which, as the pipe rests down upon the bottom of the fire-box, prevents it from twisting and turning. This is quite important, because the perforations *d*³ are preferably provided, as shown, in the 55 lower part of the pipe on each side; and if the pipe twisted or turned, these perforations would become displaced. In forming the perforations in the pipe, they are preferably arranged nearer together at the outer end of 60 the fire-box in order to provide sufficient heat at this portion of the fire-box to offset the loss due to radiation. The end of the perforated portion of the pipe is closed, and for this purpose may be pounded down to 65 a chisel edge as shown. The angle sections

of the pipe may be formed in any suitable way as by providing elbows at these points rather than by actual bending.

In the open end of the pipe, there is formed a notch *e*¹ to receive and steady the steam injector pipe, as shown in the dotted lines. This steam injector pipe connects with a suitable steam main, indicated at *h* in Figs. 1 and 3. It will be seen, moreover, that the upwardly projecting end of the pipe 75 into which the steam is delivered from the injector, is offset by means of the angles so that it does not interfere, as was stated above, with the free access to the fire-box through the fire-box door *f*. It will also be 80 seen that the open end of the pipe, into which the steam delivers and entrains the air, is removed from the fire-box door and hence the liability of entraining ashes from the fire-box to clog the draft producing apparatus is remote.

The fuel-bed is piled upon the perforated portion of the pipe which thus serves to distribute the draft throughout the body of the fuel. It will be obvious that the improved pipes are readily insertible into and removable from the fire-boxes and offer a very ready and convenient means of applying a forced-draft to almost any kiln. They may be easily constructed and are 95 convenient to ship whereby they constitute a very useful and simple element for this purpose.

In accordance with our invention, as hereinbefore disclosed, we provide in combination with means to supply steam or other gas under pressure a portable draft supply pipe operatively related to said supply means and arranged to be removable at will from the brick kiln and to be transferred 100 to another kiln. The said portable draft supply pipe has a perforated portion for embedment in the fuel and, as hereinbefore set forth, means are arranged relatively to the perforated portion of the pipe to cause 110 the pipe, when placed upon the fuel support, to position itself, thereby to bring about a predetermined relation of the perforations thereof to the fuel.

It will be evident from the foregoing description that we have provided a brick kiln containing in combination a fire chamber having a fuel support therein, an elongated, hollow draft device having a downwardly facing, exposed, under side with downwardly directed draft orifices in said under side beneath overlying portions of said device, such device being supported in said chamber and above said fuel support in such position as to become embedded in the fuel 125 deposited in said fuel support, means being also provided, as hereinbefore set forth, to project the necessary air for combustion through said orifices toward said fuel support and into the fuel-underlying portions 130

of said draft device, thereby to promote combustion of said fuel without blowing out the top of said fuel. The fire chamber is provided with a firing door to permit fuel to be deposited therein above the draft device. Preferably also we project the necessary air to effect free and complete combustion.

In the disclosed and preferred embodiment of our invention, we provide a series of fire chambers, each communicating with the interior of the kiln and each having a door opening to the exterior of the kiln, an imperforate fuel support and an elongated, hollow draft device having a downwardly facing, exposed, under side with downwardly directed draft orifices as heretofore described, said device being supported in said chamber above but adjacent to the imperforate fuel support. We also provide means to project the necessary air for combustion through said orifices toward and against said fuel support to effect by impact thereof a communication of said air supply and reversal of its direction into the fuel on said support to promote combustion thereof without blowing objectionable holes in its surface. Preferably we project the necessary air for free and complete combustion for this purpose. It is desirable to have the orifices on the under side of the draft supply pipes as distinguished from having them on the side thereof, since if a jet of air or steam issues from the side, it would not be scattered and go up disseminated through the fuel. Furthermore, unless the draft pipes were embedded in the fuel, said pipes, when the draft is cut off preliminary to stopping the furnace, thus stopping the entrance of cold air into the pipes and thus preventing the cooling of the same by the air, would become so heated as to be destroyed unless made of the best heat-resisting metal, which is more or less expensive, whereas if said draft pipes were embedded in the fuel, the excessive heating of the pipes would be largely prevented, especially if the air be discharged downwardly and below the main mass of the fuel and percolate through the interstices between the particles of coal and around the outside of the draft pipes.

The manner of operating the improved kiln is much the same as was described with reference to our kiln shown in the Letters Patent above referred to. The fires are started, fed and regulated as there set forth. In the present case, the fuel covers and rests directly upon the pipe *d* which is embedded, as it were, in the body of fuel (indicated at *i*, Fig. 2), the latter being replenished as it burns away by piling on more fuel until, if required, the fuel reaches nearly to the top of the fire-box. It is obvious that in some cases it may be preferable to bank

ashes or the like over the pipe *d* and then apply the green coal above the ashes, all of which is immaterial to the present invention.

It will be observed, by reference more particularly to Fig. 2 of the drawing, that the draft is delivered to the bed of fuel in a direction away from that of the draft exit which takes place herein up through the fuel-bed, through the arches, and into the kiln. The fuel support, in the present case, is constituted by the bottoms of the fire-boxes *b*; but it is immaterial what the nature of the fuel-support is or whether it is imperforate or not, so long as the draft is delivered relative to the fuel-body as herein set forth. In any case, the draft would be delivered in the same way, namely, by projecting the same from a plurality of points between the fuel supports and the normal level of the fuel and in a direction away from or opposite to that of the draft exit. This direction of draft delivery will, in general, be downward as in the case of Fig. 2 of the drawing; and the draft thus delivered will be distributed uniformly throughout the whole fuel-body. It will not shoot through the top thereof in spots, burning out these spots and leaving other spots partially or wholly unburned, but will do its work uniformly and thoroughly. Moreover, in the preferred construction the draft cannot pass out through the sides of the fire-spaces because the side walls thereof are draft-proof, as before explained; and hence, even when the fuel becomes banked for a considerable depth over the draft delivery pipe and constitutes a considerable obstruction to the passage of the draft, as where very fine fuel is employed, the draft nevertheless, can find no path of least resistance through the side walls and hence must pass up through the body of the fuel. It will be obvious that as the burning proceeds, this body of fuel will contain a great deal of ashes and unburnt matter, all of which will be understood as being referred to when the terms "fuel-body," "fuel-mass," or "fuel" are used herein.

We claim as our invention:

1. In a brick kiln, the combination with a fuel-support, of downwardly delivering draft means arranged above the same but below the normal level of fuel thereon so as to be covered by the fuel, whereby the draft may be delivered within the fuel mass and in a direction toward said fuel-support.
2. In a brick kiln, the combination with the arches, of a fuel-space at the end of each arch and below the same, a pipe running along the bottom of each fuel-space so as normally to be covered with fuel and having openings to deliver downwardly into said fuel-space.
3. In a brick kiln, the combination with a

fire-arch of a fuel-space therefor, draft-proof walls on each side of said fuel-space, and means supported at the bottom of said fuel-space and provided with openings to 5 deliver a forced-draft thereto in a downward direction.

4. In a brick kiln, the combination with a fire-arch of a fuel-space therefor, draft-proof walls on each side of said fuel-space, 10 and a pipe supported at the bottom of said fuel-space and provided with openings to deliver a forced-draft thereto in a downward direction.

5. In a brick kiln, the combination with 15 the arches, of a fuel-space at the end of each arch and below the same and having draft-tight side walls, a pipe supported upon the bottom of each fuel-space and having openings to deliver downwardly into said fuel-space.

6. A brick kiln having a floor formed 20 with a plurality of grateless depressions to constitute the fire-boxes, and a pipe lying along the bottom of each depression adapted 25 to supply a forced-draft thereto, the bricks to be burned being laid upon the floor to form arches above the said depressions respectively.

7. A brick kiln having a permanent floor 30 structure formed with a plurality of rows of grateless depressions the side walls of which are air-tight, and means along the bottom of each such depression to supply a forced-draft, the bricks to be burned being laid 35 upon the floor to form arches above the depressions respectively.

8. A brick kiln having a permanent floor 40 structure formed with a plurality of rows of depressions the bottoms and side walls of which are air-tight, and a pipe lying centrally along the bottom of each depression adapted to supply a forced-draft thereto, the bricks to be burned being laid upon the floor to form arches above said depressions 45 respectively.

9. A brick kiln containing in combination, 50 a fire chamber having a fuel support therein, an elongated, hollow, draft device having a downwardly facing, exposed, under side with downwardly directed draft orifices in 55 said under side beneath overlying portions of said device, said device being supported in said chamber and above said fuel support in such position as to become embedded in 60 the fuel deposited on said fuel support, said chamber having a firing door to permit fuel to be deposited therein above said draft device, and means to project necessary air for free and complete combustion through said 65 orifices toward said fuel support and into

the fuel underlying portions of said draft device, thereby to promote free and complete combustion of said fuel without blowing out the top of said fuel.

10. A brick kiln comprising in combination, 65 a series of fire chambers, each communicating with the interior of the kiln and each having a door opening to the exterior of the kiln, an imperforate fuel support, an elongated, hollow, draft device having a 70 downwardly facing, exposed under side with downwardly directed, draft orifices in said under side beneath overlying portions of said device, said device being supported in said chamber above but adjacent to the imperforate fuel support, and means to project necessary air for free and complete combustion through said orifices toward and against said fuel support to effect by impact therewith a comminution of said air supply and 75 reversal of its direction into the fuel on said support to promote combustion thereof without blowing objectionable holes in its surface.

11. A brick kiln containing in combination, 80 a fire chamber having a fuel support therein, an elongated hollow draft device having a downwardly facing exposed under side with downwardly directed draft orifices in said under side beneath overlying portions of said device, said device being supported in said chamber and above said fuel support in such position as to become embedded in the fuel deposited in said fuel support, and means to project necessary air for 85 combustion through said orifices toward said fuel support and into the fuel underlying portions of said draft device, thereby to promote combustion of said fuel without blowing out the top of said fuel.

12. In a brick kiln, the combination with 90 means to supply steam or other gas under pressure, of a portable draft supply pipe operatively related thereto to receive said air or other gas and arranged to be removable 95 therefrom at will and transferred to another kiln, the said pipe having a perforated portion for embedment in the fuel and means arranged relatively to the perforated portion to cause the said pipe, when placed upon the fuel support, to position itself thereby to bring about a predetermined relation of perforations to fuel.

This specification signed and witnessed this 25th day of March, A. D. 1911.
